UNITED STATES PATENT OFFICE.

JOHN H. HANSON AND JOHN W. STEELE, OF CHICAGO, ILLINOIS.

FUSE-PLUG.

1,103,411.

Specification of Letters Patent. Patented July 14, 1914.

Application filed April 12, 1913. Serial No. 760,650.

To all whom it may concern:

Be it known that we, JOHN H. HANSON and JOHN W. STEELE, citizens of the United States, residing at Chicago, in the county 5 of Cook and State of Illinois, have invented certain new and useful Improvements in Fuse-Plugs, of which the following is a specification.

The object of this invention is to produce 10 a fuse plug of novel and improved construction, and the invention refers more particularly to a plug provided with a plurality of fuses arranged to be successively brought into service, such plugs being known as 15 multiple fuse plugs.

In the accompanying drawings, Figure 1 is a longitudinal vertical section through a fuse plug embodying the features of our invention. Fig. 2 is a plan view with the closing cap removed. Fig. 3 is a perspective view of the core. Fig. 4 is a transverse section through the plug in the plane of line 20 4 4 of Fig. 1.

The preferred form of our invention is 25 shown in the drawings and will be herein described in detail, but it should be understood that the invention is not limited to the exact structure disclosed, but may be embodied in various modified forms without 30 departing from the scope of the invention as defined in the appended claims.

The plug comprises a sleeve 5 of insulating material and a central insulating core 6 fitting in said sleeve. Said core is provided 35 with a plurality of openings or chambers 7 extending longitudinally therethrough, each of said openings containing a fuse 8. In the preferred form shown in the drawings four fuses are provided, but it 40 will be understood that the plug may be adapted for a larger or smaller number of fuses if desired. The fuses may be arranged in pairs, each pair being formed from an integral strip of fuse wire, the middle portion 45 of the strip being bent around the lower end of the wall between two of the fuse chambers 7. A metallic contact button 10 has its shank secured in a central recess 11 in the core, the head of said button fitting in 50 a recess 12 in the lower end of the core and being in contact with the lower ends of all of the fuses 8 or, in other words, with the middle portions or bends of the strips constituting said fuses. The free 55 upper end of the strips which constitute the fuses 8 are bent outwardly to overlie the up-

per end of the core, and the extreme ends of the fuses preferably are bent downwardly into recesses 13 in the outer surface of the core. Said fuses may, if desired, be secured 60 in said recesses by plaster of Paris or other suitable material. The lower end of the core has a head 14 formed thereon which underlies the lower end of the sleeve 5 when the parts are assembled together. The upper 65 end of the core has a plurality of walls 15 extending upwardly therefrom, said walls forming partitions separating the upper ends of the openings 7 and the exposed ends of the fuses 8 from each other. When the 70 core is inserted into the sleeve 5, the upper ends of the walls 15 preferably lie substantially flush with the upper end of said sleeve.

A metallic shell 16 surrounds the sleeve 5, said shell being spirally indented to form a 75 screw thread to engage with the core 5 and also in the socket in which the plug is placed. A contact piece 17 extends through the side of the sleeve 5, the outer end of said contact piece being soldered or otherwise secured to the shell 16, and the inner end of said piece being arranged to contact one of the fuses 8 as clearly indicated in Fig. 1. Thus only one of the fuses is in service at a time. The contact piece 17 serves to secure 80 the shell 16 rigidly to the sleeve 5. If desired, interlocking indentations 18 may be formed in said shell and sleeve at the side opposite to the contact piece 17 to further assist in locking these parts together. 90

In order to more fully insulate the fuses from each other and prevent short circuiting between the fuses, we provide lugs 19 projecting inwardly from the sleeve 5, said lugs abutting against the partition walls 15 on 95 the core and completely closing the upper ends of the fuse chambers. The lug which lies above the contact piece 17 is provided at its inner end with an opening or notch 29 for the purpose of venting the fuse chamber beneath it, as will be latter described. Said lug forms a rigid backing for the contact piece 17 and serves as an insulating cover therefor.

The sleeve 5 has an enlargement or exterior flange 20 at its upper end. A metallic cap 21 having a flange 22 at its edge fits downwardly over the flange 20, said cap 21 being secured in place preferably by bending the lower edge of the flange 22 into an 100 annular groove 23 in the periphery of the flange 20. The lower corner of the flange 110

20 serves as an insulating wall between the cap 21 and the shell 16. The cap 21 has a central opening 24 therein, and between said cap and the upper face of the sleeve 5, flange 5 20 and core 6 is placed a sheet 25 of mica or other suitable translucent material. An annular vent groove 26 is formed in the upper face of the flange 20 of the sleeve 5, and this groove communicates with the atmosphere 10 through a pair of grooves 27 in the edge of said flange, one of the latter grooves preferably being positioned directly opposite the contact piece 17. A groove 28 in the upper face of the sleeve 5 connects the 15 groove 26 with the opening or notch 29 extending vertically through the lug 19 which lies above the contact piece 17. The purpose of the grooves 26, 27 and 28 and the opening 29 is to permit the escape of gas from 20 the interior of the plug when a fuse is melted.

In use, when the active fuse "blows," the plug will be unscrewed from its socket, the core 6 withdrawn downwardly out of the 25 sleeve and given a partial rotation to bring a new fuse into place, and the core then again inserted into the sleeve to carry the new fuse into contact with the piece 17. When all of the fuses in the core have been 30 destroyed, the old core may be thrown away and a new one full of fresh fuses inserted into the sleeve. When the plug is screwed tightly into its socket, the pressure exerted on the contact button 10 will clamp the fuse 35 8 tightly between the upper end of the core and the contact piece 17.

In the exemplary form of our invention which we have shown in the drawings, the central core 6 is non-circular or polygonal 40 in cross-section and the interior of the sleeve is correspondingly shaped to receive the core. Where four fuses are used, the core may be four-sided, as indicated most clearly in Fig. 3, the corners of the core preferably 45 being beveled off as at 9. It should be understood, however, that our invention is not limited to a core which is non-circular in cross section. It is desirable to form the core and the sleeve in such a way that they 50 will interlock to prevent relative rotation thereof when the core and sleeve are in their normal or operative position. The non-circular shape of the core acts to prevent such 55 relative rotation, and the same purpose is effected by the lugs 19 and the partition walls 15 which interlock when the core is in its operative position. Therefore, it will be seen that when the interlocking parts 15 and 19 or their equivalents are used, the core 60 need not necessarily be made non-circular, and on the other hand when the core is made non-circular, it is not necessary that the parts 15 and 19 be arranged to prevent relative rotation of the core and the sleeve. When the 65 core is made non-circular, as shown in the

drawings, it must be fully withdrawn from the sleeve before rotation to position the new fuse, but it will be readily understood that if the interlocking relation of the lugs 19 and walls 15 or their equivalent means, be depended upon to prevent relative rotation, the body of the core might be made circular in which case it would be necessary to move the core longitudinally or axially merely a sufficient distance to disengage the interlocking portions 15 and 19, when the core could be rotated within the sleeve. Thus it is not essential according to our invention that the core be fully withdrawable from the sleeve, but on the contrary a non-withdrawable core 70 might be used, it being necessary only that the core have a longitudinal or axial movement in the sleeve a sufficient distance to disengage the interlocking portions of the sleeve and the core, so that they may be relatively rotated to position a new fuse. 75

We believe ourselves to be the first to produce a fuse plug comprising an inner and an outer part normally interlocked to prevent relative rotation and movable longitudinally or axially into position to permit of such relative rotary movement. 80

It will be noted that in our plug a new fuse may be substituted after a "blow-out" 85 in an extremely short time and with very little trouble. No screws or like fastenings secure the fuses in place. It will also be seen that no spring contacts are employed, such springs being undesirable because likely to become overheated and untempered. All of the fuses not in use are carefully insulated from the active fuse to prevent accidental short circuits. 90

We claim as our invention:

1. A fuse plug comprising an outer member of insulating material, a threaded metallic shell secured thereto and adapted to be screwed into a socket, an inner member, a plurality of fuses carried by one of said members, and a contact piece carried by the other member and adapted to contact with one of said fuses, said members having portions engaging each other and preventing relative rotation thereof when in their operative relation, and said members being relatively movable in a direction to disassociate said engaging portions. 100

2. A fuse plug comprising an outer member of insulating material, a metallic threaded shell secured thereto and adapted to be screwed into a socket, a contact terminal carried by said shell, an inner member, a plurality of fuses carried by said inner member and arranged to be successively brought into operative relation to said terminal by relative rotation of said members, said members being shaped to engage each other to prevent relative rotation when in their normal position, and said members being longitudinally movable with respect to each other 115 120 125 130

into position to separate the engaging portions of said members.

3. In a fuse plug, a body comprising a sleeve-like portion closed at one end, said body having a non-circular opening therein, a central insulating core wholly inclosed except at one end by said body, said core having a portion fitting in said opening to prevent rotation of the core when in its operative position, and a plurality of fuses carried by said core, the core being longitudinally movable to withdraw said portion from said opening, whereby the core is free to be rotated to carry a new fuse into operative position.

4. A fuse plug comprising an outer body portion of insulating material, having secured thereto a threaded metallic shell adapted to be screwed into a socket, said shell having a contact portion, a central insulating core in said body portion, said core and body portion having engaging parts to prevent relative rotation when in their operative relation, and a plurality of fuses carried by said core, said core being arranged to have a movement longitudinally of its axis and also a rotation about its axis to successively position said fuses in operative relation to said contact portion.

5. In a fuse plug, a body comprising a sleeve-like portion closed at one end, said body having a non-circular central opening, a withdrawable core wholly inclosed except at one end by said body, said core having a non-circular portion, said opening and said core-portion being shaped to permit insertion of said portion in said opening in any one of several positions, said core having a plurality of longitudinal openings therein, a fuse in each of said openings, and a conductor carried by said body portion with which conductor one of said fuses is arranged to contact.

6. A fuse plug comprising an insulating sleeve, a metallic shell surrounding said sleeve, an insulating core fitting into said sleeve and withdrawable therefrom, an enlarged head on the lower end of said core, said head extending laterally beneath the lower end of said shell and forming a finger piece by which the core may be withdrawn, a fuse carried by said core, and a contact piece extending through said sleeve, said contact piece contacting said metallic shell at its outer end and being arranged to contact said fuse at its inner end.

7. In a fuse plug, a body comprising a sleeve-like portion closed at one end, said body having an internal opening, an insulating core adapted to enter said opening, said opening and said core being wholly inclosed except at one end by said body, said core being shaped to permit the insertion of the core in the opening in any one of several positions, said core and said body portion

having parts engaging each other to prevent relative rotation when the core is in its operative position in said body portion, and a plurality of fuses carried by said core, said body portion having a conductor arranged to contact with one of said fuses at a time, when said core is placed in said body portion in different positions.

8. A fuse plug comprising an insulating sleeve, a metallic shell secured thereto, a core fitting in said sleeve, said core and sleeve having engaging portions which prevent relative rotation of the sleeve and core when the latter is in its normal position, a plurality of fuses carried by said core, a contact piece connected with said shell and arranged to contact one of said fuses, and partition walls on one end of said core acting to separate and insulate the upper end of the fuses from each other.

9. A fuse plug comprising an insulating sleeve, a metallic shell secured to said sleeve, an insulating core extending into said shell and fitting in an opening in said sleeve, said core and said sleeve having engaging portions which prevent relative rotation of the core and sleeve when in their operative relation, a plurality of fuses carried by said core, a conducting portion connected with said shell and arranged to contact one of said fuses, partition walls on one end of said core arranged to separate said fuses from each other, said partition walls and said sleeve forming recesses, and inwardly projecting lugs on said sleeve arranged to close the upper ends of said recesses.

10. A fuse plug comprising an insulating sleeve, an annular threaded metallic shell secured thereto and adapted to be screwed into a socket, an insulating core polygonal in cross section extending into said shell and fitting in a corresponding central opening in said sleeve to prevent relative rotation of the core and sleeve when in normal relation, said core being withdrawable longitudinally from said central opening to permit such relative rotation, a contact-piece connected to said shell, and a plurality of fuses carried by said core and arranged to singly contact said contact-piece when the core is in different positions.

11. A fuse plug comprising an insulating sleeve, an annular threaded metallic shell secured thereto and adapted to be screwed into a socket, a central insulating core, said sleeve and said core having interengaging parts which prevent relative rotation of the sleeve and core when in their operative relation, said core being movable longitudinally to separate said engaging parts and permit such relative rotation, a cap fixed to and closing the end of said sleeve opposite to that from which said core enters, a plurality of fuses carried by said core and arranged to singly contact at their upper ends

with a part connected to said shell when the core is in different positions, and a contact button fixed in the end of the core opposite to said cap and being exposed on the surface so as to contact with a portion of the socket, the lower ends of all of said fuses being in contact with said button.

12. A fuse plug comprising a body, a core having a plurality of fuses, portions of which are exposed on the outer surface of the core, said core having partition walls separating said exposed portions from each other, and said body having inwardly extending lugs coöperating with said partition walls to further insulate such exposed portions.

13. A fuse plug comprising a body portion, a core therein having a plurality of recesses, fuses in said recesses, and lugs on the body portion projecting inwardly and lying in said recesses to prevent relative rotation of the body and the core, the latter being axially movable to disengage the recesses and the lugs and permit rotation of the core.

In testimony whereof we affix our signatures in the presence of two witnesses.

JOHN H. HANSON.
JOHN W. STEELE.
